UNITED STATES PATENT OFFICE

SIMON L. WARREN, OF QUINCY, MASSACHUSETTS

UPHOLSTERY-SPRING-ATTACHING DEVICE

Application filed April 25, 1928. Serial No. 272,707.

In the construction of upholstery it is common practice to mount a series of spiral springs on a support which consists of a series of interwoven strips of webbing attached to the frame. In these constructions it is customary to secure the springs in position on the webbing by attaching the end coils of the springs thereto by means of string, which is passed thru the webbing and tied about the 10 coils at different points. This arrangement has been found to be unsatisfactory for several reasons, primarily because, in use the string is subjected to wear and eventually breaks, with the result that the springs become 15 detached from the webbing and are likely to move into various inclined positions with relation to the supporting webbing with well known consequences. Also springs tend to turn axially so as to slip out from their 20 fastenings with similar results. This form of connection is further objectionable on account of the labor cost incidental thereto.

The object of my invention is to produce an improved means for attaching the end 25 coil of a spiral or similar form of spring to a textile support, so that the connection between the coil and support will not subsequently be broken even after long use and will firmly secure the spring in the position 30 in which it is attached, so that it cannot turn or otherwise move from such position, and which will enable the springs to be rapidly attached, so that labor costs may be reduced.

I accomplish this object by providing a 35 form of staple having an elongated saddle portion from which relatively narrow prongs project at the opposite ends of the sides thereof, the saddle portion of the staple being adapted to be closely fitted onto the top side 40 of the coil, so that, when the staple is placed astride the coil, the prongs may be passed through the support and the saddle portion forced onto the coil and then the prongs may be bent in opposite directions, so that they 45 lie side by side beneath the coil, whereby the coil and support will be clamped together between the saddle portion and prongs of the staple and the saddle portion will be tightly engaged with the coil, so that the coil cannot 50 move longitudinally in the staple and will

thus be held against all motion on the support.

For a more complete description of my invention, reference is made to the following specification, in connection with the accompanying drawing in which:—

Fig. 1 is a plan view of a portion of webbing support for the spiral springs of an article of furniture, illustrating the application of an embodiment of my invention 60 thereto.

Fig. 2 is a sectional view thereof on line 2—2 of Fig. 1.

Fig. 3 is a view of the blank from which a 65 staple embodying my invention is formed.

Fig. 4 is a perspective view of the finished staple.

Figs. 5, 6, 7 and 8 are detail views illustrating the manner in which the staple is applied.

According to my invention I provide a staple which is preferably formed from bendable sheet metal and comprises a somewhat elongated semi-cylindrically shaped saddle portion *a*, having edges *a'* from the opposite ends of which a pair of prongs *b* project in approximately parallel relation, the formation being such that the opposite side edges of the prongs and the opposite end edges of the saddle portions are continuous and disposed in parallel planes, the adjacent edges of the prongs being extended obliquely to meet their opposite edges, so that the ends of the prongs will be pointed.

In practice the staple will preferably be 85 formed from a flat sheet metal blank, shaped as indicated in Fig. 3, the saddle portion then being bent into U-form so that the prongs project from the opposite ends of the opposite side edges thereof in approximate parallelism. As the spring coils to which the staples are applied are practically invariably formed of round wire, the saddle portion of the staple will be formed semi-cylindrically, to fit closely on the wire of the particular size 95 of which the springs are constructed. The sides of the saddle portion are preferably extended in parallelism for a short distance beyond the semi-cylindrical portion, so that its 100 end will be somewhat more than half the

diameter of the wire. The width of the prongs at their points of connection with the saddle portion is preferably approximately half, or not more than half the length of the 5 saddle portion, as shown in Fig. 3, and, as they taper from this point to their ends, and are diagonally disposed at opposite ends of the saddle portion, they may be bent flatwise beneath the saddle portion at right angles to 10 the sides into positions in which they will lie side by side without coming in contact with each other.

The ordinary upholstery construction in connection with which the above described 15 staple is used is indicated in Figs. 1 and 2 and comprises two parallel series of interwoven strips of webbing W, which extend from opposite sides of a frame, and are drawn taut, to form a resilient support for a series of 20 spiral springs, one of which is indicated, and the bottom coil S of which rests directly on the webbing.

In attaching a spring to the webbing, after it has been placed in the desired position 25 thereon, several of the staples, usually at least three, are employed for each spring. In placing a staple in position, it is placed astride the coil, then its saddle portion is forced thereon and its prongs are forced down 30 through the webbing, preferably at some point at which two strips cross each other, so that the prongs will pass through both strips, as shown in Figs. 1 and 2, and the saddle portion will be passed onto the top portion 35 of the coil until it is firmly seated therein, as shown in Fig. 5. Then, while the saddle portion is held down on the coil, the prongs will be bent in opposite directions, to positions approximately at right angles to their former 40 positions, so that they lie side by side in engagement with the webbing directly beneath the coil. The prongs are then clenched against the webbing while the top of the 45 staple is held against some form of anvil, so that the coil and webbing are securely clamped together between the saddle portion and the prongs.

The operation of inserting and clenching the staples may be performed in any convenient manner, a method which has been found 50 to be the most effective in practice being to hold the saddle portion of the staple between the jaws of a pair of pliers, the ends of which have been recessed to receive the saddle portion, then, while thus held, to place the staple in position on the coil, as above described, and bend the prongs oppositely and 55 clamp them firmly against the webbing with a hammer, the tool with which the staple is held 60 acting as the anvil to hold the saddle portion against the coil while the prongs are being clenched. The action of bending the prongs towards the opposite sides of the saddle portion and beneath the coil and of clenching 65 them, as above described, tends to draw each

side of the saddle portion inward against the coil, so that the latter is clamped firmly between the sides of the saddle portion *a* shown in Fig. 8, the portions of the saddle below the middle of the coil usually being drawn inward, thereby increasing the force of the clamping engagement of the staple with the coil, so that the coil is securely held against either longitudinal, or swinging movement with relation to the staple. 75

When a sufficient number of staples have thus been secured to the coil of a spring and to the webbing, the coil will be securely held against any turning or sliding movement on the webbing, so that it can not be displaced by 80 use. If, for example, a coil rests principally on one strip of webbing, but overlaps onto the edge portion of an adjacent strip, a staple connecting the coil and the adjacent strip will prevent the coil from slipping therefrom, an 85 occurrence which is likely to take place with previously employed methods. Also by having the staples pass through the strips where they cross each other, all the strips will be held in the same relation as that when originally drawn tightly and attached to the frame, even though the strips become stretched in use and there is a strong tendency, by the action of the springs thereon, to push the strips away from each other at their 90 middle portions.

The arrangement of the relatively narrow prongs at the opposite ends of the saddle portion is of vital importance, as it enables them to be bent in opposite directions beneath the 100 coil without having either encounter the other, or become imposed one on the other, so that a maximum portion of the surface of the webbing will be engaged thereby. Also if the prongs were so held that their adjacent 105 edges engaged or were forced in too close proximity when they were clenched, they would have a shearing action on the strands of the webbing between them. The prongs of each staple are, however, spaced apart 110 sufficiently to prevent such an occurrence, as indicated in Fig. 6.

With the above described construction the coil may be quickly attached to the webbing, particularly when a special tool for the purpose is employed, and a connection is provided therebetween which will last indefinitely, as the staples will not become worn and the connection is such that there is no looseness which would cause any wear on the 120 webbing. 115

I claim:

1. A metal staple, for attaching an end coil of an upholstery spring to a textile support, having an elongated U-form saddle portion adapted to be closely fitted onto and clamped to the coil, to prevent longitudinal movement thereof in said saddle portion, and having a prong of substantially less width than the length of its saddle portion extending from 125 130

- each side of said portion at opposite ends and constructed to permit each prong to be bent into positions in which it extends directly beneath the side of the saddle portion opposite thereto and between its end and the prong which extends therefrom. 5
2. A metal staple, for attaching an end coil of an upholstery spring to a textile support, having an elongated U-form saddle portion of a depth substantially greater than half the diameter of the wire which forms the coil and adapted to be closely fitted thereon, and having a prong of substantially less width than the length of its saddle portion extending from each side of said portion at its opposite ends, to permit the edge portion of each side of the saddle portion to be bent beneath the coil towards the other side and each prong to be extended beneath the opposite edge portion between its prong and its end opposite thereto. 10
3. A metal staple, for attaching an end coil of an upholstery spring to a textile support, having an elongated U-form saddle portion adapted to be closely fitted onto and clamped to the coil, and having a prong, which is narrow as compared with the length of the saddle portion, extending from each side thereof at its opposite ends, providing an edge portion on each side which extends right angularly to the prong thereof and which is opposite the prong on the other side, each prong being adapted to extend beneath the edge portion opposite thereto, when bent right angularly to clamp the support and coil between the same and the saddle portion, the width of the portion of the prong directly beneath the edge portion, when in this position, being substantially less than the length of the edge portion. 15
4. In an upholstery construction including a textile support and a wire coil spring having its bottom coil seated on the top side thereof, a metal staple having an elongated U-form saddle fitted onto the top side of said coil and clamped thereto and having a prong of substantially less width than the length of the saddle extending from each side thereof at its opposite ends, said prongs being extended downwardly thru said support and bent oppositely therebeneath and beneath the corresponding directly opposite side portions of the saddle, in position to clamp the coil and support together between the prongs and the saddle. 20
5. In an upholstery construction including a textile support and a wire coil spring having its bottom coil seated on the top side thereof, a sheet metal staple having an elongated, U-form saddle fitted onto the top side of said coil, and having a flat prong of substantially less width than the length of the saddle extending from each of its sides at its opposite ends, so that each side has a bottom edge extending from the prong thereof which is directly opposite the prong of the opposite side, said prongs being extended downwardly thru said support and bent oppositely therebeneath and beneath the corresponding directly opposite bottom edge of the saddle, in position to clamp the coil and support together between the prongs and the saddle. 25
- In testimony whereof, I have signed my name to this specification.
